EXPLOSIVE RELEASE IGNITION ASSEMBLY
Walter L. Dahl, Greenfields Village, Woodbury, N.J., assignor to E. I. du Pont de Nemours and Company, Wilmington, Del., a corporation of Delaware
Filed Aug. 30, 1963, Ser. No. 305,633
6 Claims. (Cl. 89—1)

This invention relates to an electrical ignition assembly that is particularly well adapted for use in electric initiators meeting the exacting requirements in miniaturization of explosive devices.

With the growing need for miniaturization in commercial and military endeavors, requirements have been set up for miniature electric initiators having specific characteristics of physical design and firing performance. For example, a current military specification calls for an electric initiator having an outside diameter not larger than 0.09 inch and a length not greater than $\frac{1}{4}$ inch. The initiator should function over a wide temperature range in response to a specific firing energy in the range of about 5000 to about 20,000 ergs supplied from a small capacitor at voltages of from 40 to 100 volts with a firing time not to exceed about 300 microseconds. The initiator should be capable of withstanding rough handling and acceleration. Even though it would be desirable to make even smaller units with even more stringent firing characteristics, the standards set forth are difficult to meet satisfactorily on a mass production basis by the types of initiators heretofore available, primarily due to the need for a suitable ignition assembly.

Presently available electric initiators conventionally employ an ignition assembly comprising a bridgewire spanning two essentially parallel lead wires, i.e., electrodes or conductors, extending into the shell from an external firing circuit and held in place by a resilient, insulating plug. The bridgewires, in the preponderance of cases, are spaced from the base of the plug and surrounded by a bead of ignition composition. One distinct drawback to the miniaturization of this type of ignition assembly is that attempts to reduce the diameter and size of the bridgewires or lead wires to provide smaller units responsive to lower firing energies results in units where the fine wires extending from the plug into the shell are vulnerable to breakage during fabrication and assembly of the initiator and are not readily soldered to provide electrical connections which function after handling and storage. In small sizes, such assemblies are extremely sensitive to double lead wire to shell static discharge. When used in explosive fasteners, bridge plugs of this variety also require excessive lengths of sealing compound behind the plug if leak-proof functioning is to be achieved.

Another type of ignition assembly heretofore used, particularly for military devices, employs a graphite film bridge. This type of assembly is generally formed by twisting together two pieces of insulated lead wire, molding the twisted wires into an insulating plastic block, and cutting the block to expose two adjacent wire ends. The two exposed wire ends are covered with a graphite or metallic film, then with at least one layer of a primary explosive composition in a lacquer-like binder. The graphite or metallic film bridge is subject to deterioration over a period of time and is subject to accidental actuation by impact.

Representative of still another approach to providing an ignition assembly which will meet the stringent requirements for a small unit generally involves the use of a beaded or rivet-shaped center electrode received in a generally cylindrical insulator and a sleeve-like output electrode which serves as a housing for a conductive ignition charge. Such an ignition assembly is subject to wild and

2

erratic variation in firing characteristics since it is exceedingly difficult to maintain the homogeneous mixture of ignition composition and conductive material, e.g., graphite, amorphous carbon, metal particles, etc., that is requisite for uniform, reliable firing of the assembly. This difficulty is magnified when the units are to be stored since agglomeration of the conductive particles is likely to increase markedly with time and the addition of any dispersing or stabilizing agent to the mix is made with the risk of radically altering the firing characteristics of the mix. Further, the assemblies of this type are susceptible to accidental actuation by stray current, static charges, and electromagnetic radiation.

The disadvantages of the prior art are avoided by the novel ignition assembly of this invention which is suitable for production in small sizes with high standards of uniformity and reliability and is especially useful in assembling explosive fasteners that are sealed both before and after actuation. The ignition assembly comprises:

(1) A plug of an electrical insulating material comprising (a) a body element of essentially cylindrical cross-section having a head portion and a smaller diameter portion, a cavity having an essentially cylindrical wall being formed in said smaller diameter portion, said cavity being concentric with the longitudinal axis of said body element, (b) a washer element of essentially truncated conical longitudinal cross-section contiguous to the base of said head portion and in peripheral engagement with the smaller diameter portion of said body element, and (c) an internal electrode-receiving zone bounded by said base, the periphery of said smaller diameter portion, and the bore of said washer,

(2) A first electrode extending through the head portion of the body element and terminating in said electrode-receiving zone,

(3) A ground-contact electrode spaced from said first electrode and extending from said zone through the head portion of said body element, the extremity of said ground-contact electrode within said zone being spaced from said cavity and spaced from the end of the first electrode in said zone by a distance at least equal to the radius of the smaller diameter portion of said body element,

(4) An electrical element of high resistance bridging the extremities of said electrodes within said zone and passing through said cavity and the smaller diameter portion of said body element, and

(5) A heat-sensitive ignition composition within said cavity and in contact with said bridgewire.

When the ignition assembly of this invention is to be used in an explosive fastener, the axis of the first electrode at its point of entry into the head portion of the body element will be essentially coincident with the plug's longitudinal axis and said electrode will have an integral inclined portion extending radially from said axis and defining an angle of declination with respect thereto, the inclined portion beginning within the head portion and terminating in the electrode-receiving zone. In this case, the ground contact electrode will be essentially parallel to but radially displaced from the plug's longitudinal axis.

As used herein, the expression "essentially" means for all intents and purposes and is not intended to denote absolute necessity. For example, an "essentially cylindrical" element is either a cylindrical element or one which is substantially cylindrical and also functionally equivalent to the cylindrical element.

The phrase "an internal electrode-receiving zone bounded by said base, the periphery of said smaller diameter portion, and the bore of said washer" is intended to require that there be a passage or pockets at least partially surrounding the smaller diameter portion of the body element and communicating with the base of the head por-

tion to accommodate the extremities of the first and second electrodes which extend from said base. Thus, the washer encloses the electrode extremities. For example, the bore of the washer adjacent to the base of the head portion can be enlarged to provide an annular passage under said base, or the bore can contain separate pockets for the respective electrode extremities separated, e.g., by a distance at least equal to the radius of the plug's smaller diameter portion. For ease of assembly, the bore of the washer can be coated with an electrically nonconductive resin before being pressed over the plug body. The use of the nonconductive resin in conjunction with the plug and washer provides an assembly in which the electrical elements are securely imbedded and resistant to the effects of shock or vibration.

In an embodiment of this invention preferred for use in initiators of small size, e.g., having detonator shells about 0.090 inch in diameter and 0.375 inch in length, the portions of the electrodes which join the bridgewire are wrapped around the plug subtending an arc of from about 30° to about 60° and the electrical element of high resistance extends through the plug at an angle of about 90° to the axis of the plug and is secured under the electrodes.

The ignition assembly may be used to initiate the explosive train of detonators, squibs, or other such explosive device. Since the ignition assembly is well adapted to manufacture in small sizes, the assembly is particularly useful in the "miniature" initiators in which the explosive train may comprise a base charge of from about 10 to about 50 milligrams of a high velocity detonating explosive and a priming charge of from about 2 to about 35 milligrams of a primary explosive. The shell for such an initiator is only about 0.09 inch in diameter and $\frac{3}{8}$ inch long, and may have a bottom coined or thinned in comparison with the side walls so that the effective energy produced by the base charge is allowed to achieve optimum initiation impulse, i.e., to focus the initiation impulse produced along the longitudinal axis of the initiator.

The ignition assemblies of this device wherein the insulating material is a rigid material such as an epoxy resin, a sintered ceramic, Bakelite, a refractory material, or the like, are particularly well adapted for use in an explosively releasable fastener since the physical configuration of the plug enables the ignition assembly to function as a mechanical seal in conjunction with a rigid member reducing the bore in the fastener above the plug and eliminates the straight-line path for detonation gases from the bore of the fastener containing the explosive train to the exterior of the fastener that exists in common bridge plugs. Consequently, gases produced upon actuation of the explosive train will not be vented or leak from the head of the fastener before or after separation of the fastener. In a preferred explosively releasable fastener, the ignition assembly of this invention is separated from the priming charge by a distance less than the gap sensitivity value of the priming charge, i.e., the maximum distance or air gap over which the priming charge can be initiated by the stimulus of the ignition composition. The bore of the fastener then preferably is stepped to be of smaller diameter in the section between the ignition assembly and the base of the plug than in the sections about the priming and base charges. In the latter case, loading of the bore of the fastener is accomplished from the end of the fastener opposite the electrical ignition assembly and the loading aperture is sealed with a closure screw. While it is not desired to be limited by theory, it is believed that this narrowing of the bore reduces the magnitude of the detonation stress on the insulating plug and permits a reduction in the thickness or height of the head portion of the plug for any given insulating material while still allowing a leak proof seal to be retained when the fastener is severed. The loading of the base charge in such a fastener can be as low as from about 20 to about 100 milligrams of a high velocity detonating explosive and the loading of the priming charge is from about 10

to about 50 milligrams. In the case of a mild steel fastener, the bore in the housing is about $\frac{1}{4}$ to about $\frac{1}{2}$ the diameter of the fastener at the section of the fastener at which release is to occur. The length of the bore in the fastener may be about $\frac{1}{4}$ inch to about 1 inch and the diameter of the bore is about $\frac{1}{12}$ inch to about $\frac{1}{8}$ inch.

In order to describe the invention in greater detail, reference is now made to the accompanying drawings in which:

FIGURE 1 is a cross-sectional view of one embodiment of an explosively-releasable fastener having an ignition assembly in accordance with this invention, greatly enlarged for clarity, and

FIGURE 2 is a cross-sectional enlarged view of an explosively-releasable fastener having the ignition assembly of this invention, a stepped bore, and a bottom closure to facilitate explosive loading.

In FIGURE 1, 1 designates the shell or housing member, e.g., a shank, a pin, a bolt, or a shaft, which mates, i.e., engages, with member 2, e.g., a nut, or otherwise one of the frame elements to be connected, for example, through screw threads. Both housing member 1 and associated element 2 can be attached to frame elements which can be of any desired configuration. The bore of housing member 1 contains a base charge 3 of a high velocity detonating explosive and a priming charge 5. Contiguous to priming charge 5 is the contoured, two diameter plug 4 of an electrical insulating material composed of head portion 4A and smaller diameter portion 4B. Washer 9, which is contiguous to head portion 4A and peripherally engages 4B, is provided with an enlarged bore adjacent the base of head portion 4A thereby forming internal electrode-receiving zone 10. The inner extremity of the plug is cavitied and an ignition charge 6 is housed in this cavity. Electrode 7 extends into the plug from an external firing circuit (not shown) and ground-contact electrode 7A is in contact with a conductive element in member 2. A bridgewire 8 of high electrical resistance connects the terminals of the electrical conductors within the plug and passes through the ignition charge contained in the plug so that this bridgewire is in direct contact with the ignition composition. Member 2 is shown threaded to housing member 1, however, member 2 may take the form of a plug screw threaded into 1 rather than the nut or separate head shown in FIGURE 1. The threads joining the housing member 1 to member 2 are set in a sealing compound, such as an epoxy cement, at the time of assembly and the sealing composition is allowed to extrude into annulus 11 which further acts to support the conductors. Due to the miniature size of this fastener, the electrical conductors 7 are wrapped around the body of the plug subtending an arc of about 90°. The bridgewire is shown in the plane of the electrical conductors for convenience, although in one embodiment it may go through the plug at an angle of about 45° to this plane and be secured under the electrical conductors. However with a larger unit, such wrapping of the electrical conductors is not necessary and the conductors may be headed for security and to form the solder lugs for bridgewire attachment. Note that in FIGURE 1, the inclined portion of the electrode 7 extends at an angle of about 135° from the portion of the electrode exterior to the plug. The angle between these two portions should be from about 90° to about 150°. At angles of 90° or less, the terminus of the inclined portion within the shell will be too far separated from the cavity for reasonable bridge wire length. At angles of greater than about 150°, the end of the inclined conductor will be within the cavity for the ignition composition thus providing an undesirable path for explosive gases to pass from the cavity to the exterior of the fastener head. Similarly, the ground-contact electrode should be positioned outside and above the ignition cavity.

In FIGURE 2 the elements are as in FIGURE 1, how-

ever, the explosively-releasable fastener is adapted for ease in loading and has a stepped bore, i.e., the portion of the bore below the ignition assembly is of lesser diameter than about the base and priming charges, and the priming charge 5 is spaced from the ignition charge 6 contained in the plug assembly. The fastener of this embodiment is loaded from the bottom and the base of the fastener is closed by a plug 12 of an extrudable composition such as lead and closure screw 13. Plug 12 retains base charge 3 in the bore of member 1 so that the threads which mate with screw 13 can be cleaned to remove any explosive before the screw is inserted.

In operation, the electrical conductors 7 are connected in an electrical firing circuit which may be either directly or remotely actuated. At the time when actuation of the device is to be effected, an electric current is applied to the electrical conductors. The passage of current through the high resistance bridgewire 8 produces heat which actuates the ignition composition 6 and thus starts the explosive train resulting in initiation of base charge 3. In applications wherein the ignition assembly is used to initiate a base charge in the bore of a fastener connecting frame elements, which may be of any configuration, forces exerted by the detonation or deflagration of the base charge, i.e., detonation wave, shock fronts, gas pressure, and piling effects, are sufficient to cause the housing 1 to be severed, due to weakening of the wall of the housing member of this section and the free space surrounding it. When the wall of the housing separates, the frame elements connected by the fastener are freed and, in response to external forces acting thereon, e.g., gravity, mechanical forces, magnetic influences, the actual forces of detonation, etc., become spatially separated. Owing to the fluid- and pressure-resistant seal formed about and by the contoured insulating plug, the frame element attached to housing member 1 and to associated element 2 are not vented to the atmosphere and, further, are not exposed to gases which may be produced upon detonation of the base and priming charges.

The pressure exerted on the fastener head 2 is attenuated by the plug and this together with the mechanical baffling of detonation gases provided by the contour of the plug prevents blow-out or leaking of the gases from the head of the fastener. The angular configuration of the electrodes and the shielding provided by the body of the plug assures that they will be securely retained in the body of the plug and will not be ejected from the fastener upon actuation of the base or breaking charge.

Accordingly, the self-sealing fastener is severed at a predetermined location (adjacent the base charge) by explosive means without destroying or undermining the strength of adjacent structures and without producing shrapnel or in any way leaking in the presence of a pressure differential at either end of the fastener either before or after separation. This fastener does not require a separate closed breech system or any other enlarged members which materially add to the cost, size, and weight of the fastener. The fastener is essentially no larger than the actual fastening member, and any number of the units can be separated in an essentially simultaneous action. The fastener is released with a minimum of violence and produces no shattering effects on the elements it connects.

The plug, which can be secured in the bore of the initiator or fastener shell by a water- and pressure-resistant sealant, e.g., a commercial epoxy resin, is constructed of a rigid, electrical insulating material which is not reactive with the ignition and priming charge. Suitable structural materials for this plug include thermosetting plastics or resinous materials such as, for example, Bakelite or epoxy resins and thermoplastics such as polyethylene, polypropylene, polyvinyl chloride, polytetrafluoroethylene, acetal resins, and the like, and refractory material such as silicon dioxide, e.g., porcelain or glass. When the ignition assembly is to be used in an explosively re-

leasable fastener as in the figures, the plug must be strong enough, e.g., by virtue of its own structural strength and the reinforcement given by the sealing means, to withstand the forces exerted thereon when pressure builds up within the bore upon detonation of the base charge. This pressure limits the usefulness of thermoplastics since a given thermoplastic may be reactive under a particular set of temperature and pressure conditions. Therefore, the choice of insulating plug material for any given application will be governed by the situation. The acetal resin manufactured by E. I. du Pont de Nemours & Company under the trade name "Delrin," fulfilled the requirements of one embodiment of this invention.

The diameter of the electrodes used in the ignition assembly of this invention can be as small as 0.010 inch and generally will be about 0.020 inch. Due to the unique assembly of the electrical element of high resistance, i.e., the bridgewire, which is provided by the plug, this ignition cavity may be as small as $\frac{3}{64}$ inch in diameter. The outer diameters will be governed by the application in which the plug is being used. The length of the portion of the electrode 7 that extends into the plug may be as short as $\frac{1}{2}$ of the total height of the plug. The length of the inclined portion of the electrode will also be governed by the application, e.g., assemblies as shown in FIGURE 1 require somewhat longer conductors than those needed with the FIGURE 2 assembly.

The walls of the ignition cavity need only be strong enough to withstand the forces exerted in charging and assembling the units. In general, the walls of the cavity may be from .015 to .030 inch thick. The ignition composition can be loaded into the cavity at various magnitudes of pressure. Usually, the pressure of compaction will exceed 10,000 p.s.i. Compaction pressures of 10,000 to 20,000 p.s.i. have been used with good results, however, pressures as high as 100,000 p.s.i. can be used, if desired. The design of the ignition assembly of this invention is particularly advantageous in loading of initiators since it is rigid and the ignition charge can be separately loaded under controlled conditions by a machine such as a rivet loader. Consequently, the initiator shell can be loaded with the main and primer charges, the plug inserted into the shell and pressed inwardly to subject the charges to the desired pressure, preferably a pressure of above 10,000 p.s.i. The plug then is sealed into the shell, e.g., by metal-filled epoxy resin, by crimping, or by swaging to confine the contents permanently under the applied pressure.

The ignition composition preferably is of a pure compound such as essentially chemically pure lead azide, e.g., as available as RD-1333 lead azide, the double salt of cesium nitrate and cesium decahydrodecaborate, the double salt of cesium nitrate and cesium dodecahydrodecaborate, the multiple salt of basic lead picrate, lead propionate and lead azide commercially available as Remington No. 8 salt, or the lead salt of dinitro-o-cresol. If desired, a binder or a graining agent may be used to aid in retaining the composition in the cavity. These compositions are initiated directly upon the passage of electricity through the resistance element with the accompanying dissipation of heat and do not require the presence of conductive particles mixed within the composition. Accordingly, there is no danger of segregation of particles of the ignition composition during storage which would result in erratic firing response and the danger of premature or accidental ignition of the initiator by the passage of spurious current through the composition is materially lessened.

The ignition assembly of this invention is conveniently prepared by installing the electrical conductors in the insulating plug head and wrapping them in arcs of about 90° around the plug body. The bridgewire is inserted by pulling it up through axial slits provided in the ignition cavity walls or, alternatively, is passed through perforations in the walls, and thereafter the protruding ends are

wrapped around the conductor legs and soldered or welded in place. The counterbore in the truncated conical insulating washer preferably is then coated with non-conductive resin, e.g., an epoxy cement, and the washer is pressed over the plug body until it seats against the plug head and encloses the conductor legs. When the epoxy resin has cured, all electrical elements are securely imbedded and virtually impervious to the effects of shock, vibration, or other disturbances.

As stated, the ignition assembly of this invention finds particular utility in actuating the explosive train in an explosively releasable fastener as shown in FIGURES 1 and 2. In such a fastener the elongated shell 1 and associated member 2 can be constructed of a metal, e.g., iron, steel, or other ferrous alloys, copper, bronze, aluminum, magnesium, etc., or of a polymeric material such as of polytetrafluoroethylene or an acetal resin ("Delrin") having the structural strength and rigidity to support the load between frame elements which the fastener or fasteners connect. When a polymeric housing is used, a contact plate or zone of an electrically conductive material is provided to act as a ground contact for the ground contact electrode. The thickness and strength requirements of shell 1 and associated element 2 naturally will depend upon the nature of the elements to be connected, i.e., the walls should have tensile strength, impact strength, and shear strength necessary to withstand vectoral forces exerted by the objects connected. The bore within the shank of the fastener preferably is made at minimum expense of the fastener strength and provided at the location where separation is desired with sufficient quantity of detonating explosive to produce a dynamic pressure pulse of sufficient force to overcome the strength of adjacent fastener walls, yet insufficient to cause brisance injurious to the adjacent connected structures. If desired, the wall of the housing may be made thinner by machining or otherwise reducing the thickness of either the inside or outside of the housing or the housing may be notched at the section at which the separation is to be effected. Naturally the length of the housing will depend upon the nature and size of charges to be used and the spacing desired between frame elements.

The explosive employed as the base or breaking charge can be a deflagrating explosive; but, in order to work the greatest economy in size while still retaining maximum fastening strength, the base charge should be an explosive which detonates at high velocity, namely a velocity greater than 1000 meters per second. While primary detonating explosives such as lead azide may be employed, preferably more powerful explosives, for example pentaerythritol tetranitrate (PETN), cyclotrimethylenetrinitramine (RDX), cyclotetramethylenetrinitramine (HMX), nitromannite, tetryl, or TNT, explosives designated as secondary explosives, are used. As the priming charge, heat-sensitive detonating compositions such as lead azide, diazodinitrophenol, or mercury fulminate can be used. As mentioned heretofore, a quantity as low as 20 milligrams of high explosive in the fastener of this invention is sufficient to sever the smaller fasteners at the predetermined section and does not cause undesirable violence and brisance. In a fastener of a given size, quantities of high velocity detonating explosives somewhat larger than the minimum breaking charge can be used, when centrally disposed in a rigid housing, without loss of the non-shattering characteristics, but this necessitates an increase in the thickness of the insulating plug to assure that a seal will be maintained after the detonation occurs; and, since the main value of this invention is its small size, the practice is to utilize the minimum explosive charge which will reliably break a given fastener.

The following examples are presented as illustrative of the present invention but is not to be construed as limiting the invention in any way.

Example 1

Twelve ignition assemblies were prepared as described

in FIGURE 2. Each plug was formed of "Delrin" acetal resin and was 0.11 inch thick, 0.089 inch in diameter over the charge cavity and 0.200 inch in diameter at the larger diameter head. The central cylindrical cavity with 0.075 inch deep and 0.045 inch in diameter and was filled with No. 8 Remington salt, a mixture of basic lead picrate, lead propionate, and lead azide, pressed at 10,000 p.s.i. The electrodes were of 26 ga., 7 x 34 stranded copper wire and the bridgewire was 0.001 in. diameter 80/20 platinum/iridium (3Ω).

Each of these ignition assemblies was inserted into the open extremity of an initiator shell (0.09 inch in diameter and 0.25 inch long) containing a base charge of 20 milligrams of HMX and a priming charge of 15 milligrams of lead azide and sealed into place. The firing characteristics of the initiators were tested by connecting the central electrode to a condenser discharge blasting machine capable of producing firing energies of 100 to 62,000 ergs at voltages of from about 10 to about 100 volts. The initiators were tested by attempting to discharge the output of the machine into the initiator by stepwise increasing the voltages used to charge the condensers and recording the energy at which the initiators functioned. The initiators were actuated reliably and uniformly when 20,000 ergs were discharged from a 250 microfarad capacitor. This level is well within the limits set forth by the military.

Example 2

Twelve faseners were prepared resembling that shown in FIGURE 2. The housing 1 of each was 0.900 inch long, and its outer diameter was 0.31 inch. The housing was threaded for essentially its entire length excepting a $\frac{1}{8}$ -inch segment adjacent to the base charge which was relieved to a diameter of 0.235 inch. The contoured bore (0.100 inch in diameter) within the housing contained 40 milligrams of HMX and 20 milligrams of lead azide. The ignition assembly was as described in Example 1 except that in this case the plugs were fabricated of Bakelite resin. One electrode extended into the housing from an external firing circuit and the other electrical conductor was grounded to the elongated housing, which was connected in the electric firing circuit.

The fasteners were fired by applying a direct current of approximately 0.5 ampere to the electrodes. The housing was severed at the section adjacent the base charge. Essentially no shrapnel was produced, and microscopic inspection and pressure studies of the fired fasteners revealed that both sections of the fastener were sealed so that neither detonation gases nor electrical conductors would come in contact with objects at the ends of the fastener and so that venting of gases to the outside atmosphere would be precluded. The severed fasteners were capable of withstanding a hydrostatic pressure of at least 50 p.s.i. from either side of either fastener segment after detonation.

As will be evident to those skilled in the art, various modifications can be made in the light of the foregoing disclosure and discussion without departing from the spirit and scope of the invention.

What is claimed is:

1. An electric ignition assembly for use in an explosive initiator which comprises:

(a) a plug of an electrical insulating material comprising (1) a body element of essentially cylindrical cross-section having a head portion and a smaller diameter portion, a cavity having an essentially cylindrical wall being formed in the smaller diameter portion, said cavity being concentric with the longitudinal axis of said body element, (2) a washer element of essentially truncated conical longitudinal cross-section contiguous to the base of said head portion and in peripheral engagement with the smaller diameter portion of said body element, and (3) an internal electrode receiving zone bounded by said base, the periphery of said smaller diameter portion, and the bore of said washer,

- (b) a first electrode extending through the head portion of the body element of said plug and terminating in said electrode-receiving zone,
  - (c) a ground-contact electrode spaced from said first electrode and extending from said zone through the head portion of the body element, the extremity of said ground-contact electrode within said zone being spaced from said cavity and spaced from the end of the first electrode in said zone by a distance at least equal to the radius of the smaller diameter portion of the body element, 5
  - (d) an electrical element of high resistance bridging the extremities of said electrodes within said zone and passing through said cavity and the smaller diameter portion of the body element, and 10
  - (e) a heat-sensitive ignition composition within said cavity and in contact with said bridgewire.
2. An explosively releasable fastener which is characterized by the absence of shrapnel, explosive gases and ejected lead wire, and by its sealed condition after functioning, comprising an elongated housing member adapted to engage with an associated element, said elongated housing having an axial bore closed at one end and containing in sequence from said end
- (a) a base charge of high velocity detonating explosive; 25
  - (b) a priming charge contiguous to and in propagating relationship to said base charge;
  - (c) an ignition assembly in propagating relationship to said priming charge, said ignition assembly being sealed in said bore by a water-and pressure-resistant sealant and comprising
- (1) a plug of an electrical insulating material comprising (a') a body element of essentially cylindrical cross-section having a head portion and a smaller diameter portion, a cavity having an essentially cylindrical wall being formed in the smaller diameter portion, said cavity being concentric with the longitudinal axis of said body element, (b') a washer element of essentially truncated conical longitudinal cross-section contiguous to the base of said head portion and in peripheral engagement with the smaller diameter portion of said body element, and (c') an internal electrode-receiving zone bounded by said base, the periphery of said smaller diameter portion, and the bore of said washer,
- (2) a first electrode extending into the head portion of the body element, the axis of said electrode at its point of entry into the plug being coincident with the longitudinal axis of said plug, said electrode having an inclined portion formed integrally therewith extending radially from said axis thereby defining an angle of declination with the portion of said electrode extending into the plug, said inclined portion be-

- ginning within the head portion of the body element and terminating in said electrode-receiving zone,
  - (3) a ground-contact electrode extending from said zone through the head portion of the body element essentially parallel to but radially displaced from the longitudinal axis of the plug, the extremity of said ground contact electrode within said zone being spaced from said cavity and spaced from the end of the first electrode in said zone by a distance at least equal to the radius of the smaller diameter portion of the body element,
  - (4) an electrical element of high resistance bridging the extremities of said electrodes within said zone and passing through said cavity and the smaller diameter portion of the body element, and
  - (5) a heat-sensitive ignition composition within said cavity and in contact with said bridgewire; and
  - (d) a rigid member secured to the extremity of said housing contiguous to said ignition assembly and reducing the diameter of the axial bore in said elongated housing, said first electrode of the ignition assembly extending through said member.
3. A releasable fastener as in claim 2 wherein the fastener is made of mild steel and loading of the base charge is from about 20 to about 100 milligrams and the loading 30 of the priming charge is from about 10 to about 50 milligrams of a primary explosive.
4. A releasable fastener as in claim 2 wherein the elongated fastener housing is of mild steel and the major diameter of the bore of the elongated housing is about 35 $\frac{1}{4}$ to about $\frac{1}{2}$ the diameter of the housing at the section of the housing to be severed.
5. An ignition assembly as in claim 1 wherein said first electrode enters the head portion of the plug on the plug's longitudinal axis.
6. A releasable fastener as in claim 2 wherein said axial bore is of smaller diameter between the ignition assembly and priming charge than it is about said priming charge and the base charge, and the ignition composition and priming charge are spaced from each other 40 by a distance less than the gap sensitivity value of the priming charge.
